UNITED STATES PATENT OFFICE

CHARLES FENSKY, OF ST. LOUIS, MISSOURI

EAR SOUND REFLECTOR

Application filed June 10, 1931. Serial No. 543,460.

This invention relates to certain new and useful improvements in ear sound reflectors.

The primary object of the invention is to provide an ear reflector or hearing device adapted to be inserted in the outer ear of a person afflicted with deafness whereby sound waves entering the device are augmented or amplified when contacting the inner ear or parts associated therewith.

A further object of the invention is to provide a device of the foregoing character and of a size to fit completely within the outer ear with means therein to reduce the escape of rebounding vibrations and other means therein to set up a vibratory action for the for the amplification of sound waves when delivered to the inner ear.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a side elevational view of an ear reflector or hearing device constructed in accordance with the present invention;

Figure 2 is a top plan view of the same;

Figure 3 is an edge elevational view;

Figure 4 is a vertical cross-sectional view taken on line 4—4 of Figure 3, showing the staggered fins or baffles to reduce the escape of rebounding vibrations or sound waves and the vibrating reed therein;

Figure 5 is a sectional view taken on line 5—5 of Figure 1, showing the screw plug section carrying the vibrating reed;

Figure 6 is a side elevational view, partly broken away and shown in section to illustrate another form of reed support;

Figure 7 is a cross-sectional view taken on line 7—7 of Figure 6;

Figure 8 is a side elevational view of another form of hearing device wherein a sound collecting hood is arranged at the outer end of the horn-like member;

Figure 9 is an edge elevational view of the device shown in Figure 8; and

Figure 10 is a detail sectional view taken

on line 10—10 of Figure 8, showing the outwardly flaring hood at the outer end of the horn-like member.

Referring more in detail to the accompanying drawings and particularly to Figures 1 to 5, the ear reflector or hearing device that is constructed of a size to be substantially hidden from view when placed in the outer ear of a person, the device comprising a hollow spherical portion 10 having an ear piece or nipple 11 of tapering formation directed outwardly from one side thereof with an annular bead 12 at its reduced end that aids in the retention of the device in the ear. A funnel or horn-like member 13 arcuate in elevation as shown in Figure 1 is carried by the spherical body 10, spaced 90° from the nipple 11, the horn-like member 13 occupying a position in the outer ear while the nipple is extended in the canal of the ear toward the inner ear.

The horn-like member 13 is open at its outer end and is in open communication at its inner end with the spherical member 10 and said horn-like member adjacent its open outer end is provided with a pair of overlapping staggered inclined baffles 14 directed toward the inner end of said member so that sound waves entering the member will be retarded in rebounding movement to lessen and greatly reduce the escape of sound waves. An annular baffle ring flange 15 is carried by the inner face of the horn-like member 13 adjacent its point of connection with the spherical member 10 and has a relatively large central opening therein through which a flexible reed extends.

As shown more clearly in Figures 4 and 5, the spherical member 10 has a screw plug 16 forming a part of the wall of said member threaded therein and to which one end of the reed 17 is attached as at 18 such as by countersinking the same and said reed 17 that is of blade-like formation to extend through the opening in the baffle ring 15 has an enlarged disk portion 19 within the spherical member 10, this disk portion 19 tending to prolong vibratory action of the reed. An inclined baffle 20 is provided in the nipple 11 as shown in Figure 5 and operates to reduce the re-

bounding of sound waves delivered to the inner ear.

In the form of invention shown in Figures 6 and 7, the structural features thereof are substantially the same as illustrated in Figures 1 to 5 except that a ring flange 21 is provided in one side of the spherical member 10a and an outwardly directed internally threaded collar 22 surrounds the ring flange 21 for the reception of a screw plug 16a. The 10 reed 17a has a bent end 18a that is positioned between the ring flange 21 and screw plug 16a to provide for clamping the reed 17a in position as illustrated in Figure 7.

From the above detailed description of the 15 invention, it is believed that the construction and operation thereof will at once be apparent, it being noted that the device is of a size to be worn within the outer ear and to be practically unnoticeable and the entire 20 device may be constructed of material possessing vibratory qualities to aid in augmentation and amplification of sound waves entering the open outer end of the horn-like member 13. The baffles 14 tend to reduce the 25 escape of rebounding sound waves, as does also the ring baffle 15 while the reed 17 greatly amplifies sound waves which are then transmitted through the nipple 11 into the 30 inner ear.

In the form of the invention shown in Figures 8 to 10, the horn-like member 13a is provided with a sound collecting hood at its 35 outer end that comprises an arcuate inclined wall 23 arranged at the outer side of the member 13a and opposite a side opening 24, the arcuate wall 23 of the hood being spaced from the adjacent side edge of the horn-like member as at 25. An inclined baffle 26 of crescent 40 shape is formed at the outer end of the hood that acts to prevent the escape of rebounding sound waves. The provision of the hood on the end of the horn-like member produces an effect similar to the cupping of the ear by a hand and acts to gather and concentrate 45 sound waves for directing them through the horn-like member. Sound waves may also enter through the space 25 for increasing the efficiency of the device.

While there are herein shown and described the preferred embodiments of the present invention, it is nevertheless to be understood that minor changes may be made therein without departing from the spirit and scope of the invention as claimed.

I claim:

1. In a device of the class described, a spherical member, a nipple projecting therefrom, a horn-like member projecting from the spherical member, and means in the horn-like member to prevent escape of rebounding sound waves.

2. In a device of the class described, a spherical member, a nipple projecting therefrom, a horn-like member projecting from

the spherical member, means in the horn-like member to prevent escape of rebounding sound waves, and a vibrating reed anchored at one end in the spherical member and extending into the horn-like member.

3. In a device of the class described, a spherical member, a nipple projecting therefrom, a horn-like member projecting from the spherical member, and inclined baffles in the horn-like member to prevent escape of rebounding sound waves.

4. In a device of the class described, a spherical member, a nipple projecting therefrom, a horn-like member projecting from the spherical member, a vibrating reed anchored at one end in the spherical member and extending into the horn-like member, and a screw plug in the spherical member for the support of the reed.

5. In a device of the class described, a spherical member, a nipple projecting therefrom, a horn-like member projecting from the spherical member, a vibrating reed anchored at one end in the spherical member and extending into the horn-like member, and said reed being transversely enlarged within the spherical member.

6. In a device of the class described, a spherical member, a nipple projecting therefrom, a horn-like member projecting from the spherical member, a vibrating reed anchored at one end in the spherical member and extending into the horn-like member, a screw plug in the spherical member for the support of the reed, and said reed being transversely enlarged within the spherical member.

7. In a device of the class described, a spherical member, a nipple projecting therefrom, a horn-like member projecting from the spherical member, a vibrating reed anchored at one end in the spherical member and extending into the horn-like member, a screw plug in the spherical member for the support of the reed, and said reed being set at one end in the screw plug.

8. In a device of the class described, a spherical member, a nipple projecting therefrom, a horn-like member projecting from the spherical member, a vibrating reed anchored at one end in the spherical member and extending into the horn-like member, a screw plug in the spherical member for the support of the reed, and said reed being clamped between a wall of the spherical member and the screw plug.

9. In a device of the class described, a spherical member, a nipple projecting therefrom, a horn-like member projecting from the spherical member, and inclined baffles in the horn-like member and nipple to prevent escape of rebounding sound waves.

10. In a device of the class described, a spherical member, a nipple projecting therefrom, a horn-like member projecting from the

spherical member, means in the horn-like member to prevent escape of rebounding sound waves, and a sound collection hood on the outer end of the horn-like member.

11. In a device of the class described, a spherical member, a nipple projecting therefrom, a horn-like member projecting from the spherical member, means in the horn-like member to prevent escape of rebounding sound waves, a sound collection hood on the outer end of the horn-like member, and arranged at the outer side thereof.

In testimony whereof I affix my signature.
CHARLES FENSKY.
